UNITED STATES PATENT OFFICE.

JOHN L. SCHINDLER, OF FRIEND, OREGON.

GOVERNOR FOR EXPLOSIVE-ENGINES.

1,102,960.

Specification of Letters Patent.

Patented July 7, 1914.

Application filed September 23, 1913. Serial No. 791,306.

To all whom it may concern:

Be it known that I, JOHN L. SCHINDLER, a citizen of the United States, residing at Friend, in the county of Wasco and State 5 of Oregon, have invented certain new and useful Improvements in Governors for Explosive-Engines, of which the following is a specification.

The present invention relates to improvements in that type of governor devices for explosive engines set forth in my prior application filed May 15th, 1913, Serial Number 767,817.

The object in the present instance is to 10 provide a throttling control for the fuel charge entering a hydrocarbon engine which will be automatically operated at a predetermined pressure of the suction through the intake of said engine, and which is accomplished by the provision of a valve on a 15 longitudinally movable shaft mounted in a threaded journal, which shaft also carries a rotary governor for imparting movement to said shaft and valve to control the operative area of the passage through said intake. In conjunction with the foregoing it is contemplated, as in my previous application above referred to, to employ tensioning means for regulating the sensitiveness of 20 25 30 operation of the rotary governor co-operating with the valve of my device.

For a full understanding of the present invention, reference is to be had to the following description and the accompanying drawings, in which:

Figure 1 is a side elevation of my governor device, partly in section to show the interior details of construction; Fig. 2 is a transverse sectional view on the line 2—2 40 of Fig. 1; Figs. 3 and 4 are similar transverse sectional views on the lines 3—3 and 4—4 of Fig. 1, respectively.

Throughout the following detail description, and on the several figures of the drawings, similar parts are referred to by like reference characters.

Referring to the drawing and specifically describing my invention, the numeral 1 represents a casing which is adapted to be inserted as a portion of the intake manifold of an explosive engine in a manner described in my prior application hereinbefore referred to. The casing preferably comprises removable reduced ends 2 and 3 having threaded connection with the main body 55 portion 1, as shown most clearly in Fig. 1

of the drawing. Mounted within the casing 1 and longitudinally of the same is a shaft 4 which is preferably journaled in a suitable frame 5 adapted to be inserted in the 60 casing. The shaft 4 carries at one end a disk valve 6 normally held adjacent its seat 7 as will be hereinafter more fully described. The valve seat 7 is formed by a transverse partition 7' located in the upper reduced end 65 2 of the casing 1. Near the opposite end of the shaft 4 said shaft is enlarged and formed with quick advancing threads 8 which threaded portion of the shaft is disposed in an internally threaded journal 9 70 75 at one end of the frame 5. Directly adjacent this threaded portion of the shaft 4 and at the lower end of said shaft is secured a fan or rotary governor 10, while disposed about said shaft intermediate its journals is 80 a spiral spring 11. One end of the spring 11 is secured to said shaft at the point indicated by the numeral 12, while its opposite end is secured to a pinion 13 which pinion is mounted free upon the shaft 4 adjacent the upper journal of said shaft, as most clearly shown in Fig. 3 of the drawing. Extending transversely through the casing is an operating shaft 14 having intermediate 85 its length within the casing a worm 15 intermeshing with the pinion 13 on the shaft 4. On an extremity of the shaft 14 exterior to the casing is a finger wheel 16 for manipulating the shaft 14 to place a greater or less tension upon said shaft.

In the use of my invention it will be understood that when the suction of the fuel charge through the casing 1 reaches a predetermined pressure sufficient to overcome the tension of the spring 11 upon the shaft 95 4, said suction pressure will rotate the fan governor 10 and thereby rotate the shaft in its threaded journal 9. The threads 8 of the shaft will cause a longitudinal movement of the same tending to thrust the 100 valve 6 toward its seat 7 to more or less close the operative opening through the casing 1 as will be obvious. The amount of charge admitted to the hydrocarbon engine will therefore be controlled and the point of 105 operation of the valve may readily be predetermined by an adjustment of the operating shaft 14 so as to increase or decrease the tension of the spring 11. As soon as the pressure of the suction through the casing 110 is reduced the valve 6 withdraws from its seat and permits the free passage of the

charge through the opening in the partition 7'.

Having thus described the invention, what I claim as new is:

5. 1. A governor for explosive engines comprising a casing, a valve in said casing, a fan governor normally inactive, a shaft connecting the valve with the governor, and means for imparting longitudinal movement 10 to the shaft to cause seating of the valve upon rotation of the fan governor by excess pressure of suction through the casing.
2. A governor for explosive engines comprising a casing, a valve in said casing, a fan governor, a shaft connecting the valve with the governor, means for imparting longitudinal movement to the shaft to cause seating of the valve upon rotation of the fan governor by suction through the casing, and 20 means for tensioning the shaft to control operation of the governor and maintain the same normally inactive.
3. A governor for explosive engines comprising a casing, a threaded shaft journaled in said casing, a valve at one end of said shaft, a seat for said valve, a rotary governor mounted on said shaft, and means coöperating with the threaded portion of the shaft whereby to impart longitudinal movement to the latter tending to seat the valve upon rotation of the governor.
4. A governor for explosive engines comprising a casing, a shaft in said casing having a threaded portion adjacent one end, a valve on said shaft, a fan governor also mounted on said shaft, and a threaded journal for said shaft for coöperation with the threaded portion of the shaft whereby to impart longitudinal movement to the latter tending to seat the valve upon rotation of the governor.

5. A governor for explosive engines comprising a casing, a frame disposed in said casing, a shaft journaled in said frame and 45 having a threaded portion coöperating with

a correspondingly threaded journal, a valve carried by said shaft, and a rotary governor connected to said shaft for rotating the latter to thereby impart longitudinal movement to the shaft whereby to cause seating 50 of the valve and closure of the passage through said casing.

6. A governor for explosive engines comprising a casing, a frame disposed in said casing, a shaft journaled in said frame and 55 having a threaded portion coöperating with a correspondingly threaded journal, a valve seat adjacent one end of the frame, a valve secured to said shaft intermediate the seat and the frame aforesaid, a fan governor for 60 rotating the shaft secured to the other end of said shaft, a spring disposed about and secured to said shaft, and means for tensioning said spring and shaft to control operation of the fan governor.

7. A governor for explosive engines comprising a casing, a frame disposed in said casing, a shaft journaled in said frame and having a threaded portion coöperating with a correspondingly threaded journal, a valve 70 seat adjacent one end of the frame, a valve secured to said shaft intermediate the seat and the frame aforesaid, a fan governor for rotating the shaft secured to the other end of said shaft, a spring disposed about and 75 secured to said shaft, a transverse operating rod extending through said casing, a worm on said operating rod, and a pinion freely mounted on the shaft aforesaid and meshing with the worm on the operating rod, whereby to regulate the tension of said spring and shaft to control operation of the fan governor.

In testimony whereof I affix my signature in presence of two witnesses.

JOHN L. SCHINDLER.
